(57) **CLAIM**

The ornamental design for dispenser cap as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of dispenser cap embodying our new design;

FIG. 2 is a right view thereof;

FIG. 3 is a front view thereof;

FIG. 4 is a left view thereof;

FIG. 5 is a back view thereof;

FIG. 6 is a top view thereof;

FIG. 7 is a bottom view thereof;

FIG. 8 is a perspective view of a second embodiment of dispenser cap embodying our new design;

FIG. 9 is a right view thereof;

FIG. 10 is a front view thereof;

FIG. 11 is a left view thereof;

FIG. 12 is a back view thereof;

FIG. 13 is a top view thereof;

FIG. 14 is a bottom view thereof;

FIG. 15 is a perspective view of a third embodiment of dispenser cap embodying our new design;

FIG. 16 is a right view thereof;

FIG. 17 is a front view thereof;

FIG. 18 is a left view thereof;

(Continued)

FIG. 19 is a back view thereof;
 FIG. 20 is a top view thereof; and,
 FIG. 21 is a bottom view thereof.
